CLAIM

The ornamental design for a sealing cap for beverage bottle, as shown and described.

DESCRIPTION

FIG. 1 is a front view of sealing cap for beverage bottle; FIG. 2 is a left-side view thereof;

FIG. 3 is a right-side view thereof;

FIG. 4 is a back view thereof;

FIG. 5 is a perspective view thereof;

FIG. 6 is a top view thereof; and,

FIG. 7 is a bottom view thereof.

The broken lines are shown for the purpose of illustrating environmental subject matter of an exemplary bottle and form no part of the claimed design.
